UNITED STATES PATENT OFFICE.

DAVID G. LORRAINE, OF LOS ANGELES, CALIFORNIA.

GAS, OIL, AND SAND SEPARATOR.

1,373,664.

Specification of Letters Patent.

Patented Apr. 5, 1921.

Application filed February 5, 1920. Serial No. 358,438.

To all whom it may concern:

Be it known that I, DAVID G. LORRAINE, a citizen of the United States, residing at Los Angeles, in the county of Los Angeles and State of California, have invented new and useful Improvements in Gas, Oil, and Sand Separators, of which the following is a specification.

This invention relates to apparatus for the efficient separation of gas and oil and especially for the separation of these substances when same are recovered from oil wells, and an object of the invention is to provide an apparatus for the effectual recovery of the gaseous content of emulsified oils as well as for the separation of oils and gas when the same is not in the form of an emulsion. The invention has also for an object to provide an apparatus in which as few parts as practicable are arranged within a separating chamber and to provide for ready access to the said parts; and another object is to provide for the arrangement and organization of other elements wholly exterior to the separating chamber so that necessary adjustments, attention, and replacements may be given and had without the necessity of dismantling or materially interrupting the operation of a plant.

30 A further object of the invention is to provide means for maintaining a pressure continuously on the oil or emulsion as it is continuously admitted to the separating chamber so that the emulsion may be subjected 35 to sufficient pressure to express the gaseous constituent of the emulsion from the mixture.

Another object of the invention is to provide effectual means for automatically controlling the discharge, separately, of the oil and gases from the apparatus and especially to provide a pneumatic device adapted to stand the pressures that may obtain within the separating chamber.

45 Another object of the invention is to provide hydrostatic means for controlling the discharge of oil and for preventing the loss of gas with the outwardly passing oil and to provide such a hydrostatic means readily 50 variable to afford different heads of oil pressure to overcome the interior pressure during the operation of the apparatus.

Another object of the invention is to provide for the minute adjustment of the oil 55 discharge mechanism.

Another object is to provide an organization in which the several parts are simple in construction, readily removable and renewable, and to provide coördinate valve means operative by a single connection with the said pneumatic control means.

A further object of the invention is to provide a novel method for treating oil emulsions to facilitate the recovery of the gaseous content of the emulsion.

With these and other objects in view the invention consists of the method, the combination and in details and arrangements of the parts, an embodiment of the invention being illustrated in the accompanying drawings and described and claimed herein.

Figure 1 is a side elevation of the improved apparatus.

Fig. 2 is a top plan view of the apparatus.

Fig. 3 is a section on line 3—3 of Fig. 2.

Fig. 4 is a section on line 4—4 of Fig. 2.

Fig. 5 is a section on line 5—5 of Fig. 4.

Fig. 6 is a detail sectional view of the upper portion of the pneumatic float.

The apparatus includes, preferably, an upright cylindrical tank or receptacle 2 of any suitable dimensions having a head 3 that has a manhole 4 which is shown in Fig. 2 as closable by a manhole plate 5. The lower end of the tank is provided with a bottom 6 having a central outlet pipe 7 in which is provided a cut-off valve 8 which, when opened, will provide for the washing out of such material as sand or other substance collecting in the bottom of the receptacle 2 and which discharge may be facilitated by the introduction of water or other fluid under pressure by the opening of a valve 9 arranged in a pressure pipe 10 at one side, and in the lower portion, of the receptacle 2.

Oil or emulsion to be treated is introduced, preferably, through the top 3 of the receptacle to which is connected a supply pipe 12 leading in through a connection 13 on the top of the receptacle and which connection is shown in Fig. 4 as including a downwardly extending tube 14 having around its lower end a sleeve or hood 15 provided at its upper portion with a gas outlet 16; the lower end of the sleeve 15 having an inclined bottom 17 below the open mouth 18 formed in the side of the sleeve and which mouth is disposed toward the ad-

jacent surface of the wall of the receptacle 2. The inlet sleeve 15 is arranged, as shown in Figs. 2 and 4, as in close juxtaposition to one side of the cylindrical receptacle; and 5 extending vertically and transversely across this receptacle there is provided a partition wall 19 the flanges 20 of which may be riveted or otherwise secured as at 21 to the interior surface of the receptacle 2.

10 The lower end of this partition 19 terminates well above the bottom of the receptacle and the partition forms a confined vertical passageway down which the oil issuing from the mouth 18 of the inlet sleeve 15 is directed and is caused to pass beneath the lower edge of the partition 20 before the lighter materials, such as gas and oils, can rise to a predetermined variable height in the receptacle. This enables the sand that 15 may be obtained in the oil or emulsion, coming from the supply pipe 12, to settle toward the bottom while the oil passes around the lower edge of the partition and ascends in the larger compartment formed on the 20 opposite side of the partition.

The accumulating gases ascending to the top of the receptacle pass into an outlet 22 and into a gas pipe 23 in which may be provided a gage 24. The outwardly passing 30 gas flows down a pipe 25 in the lower end of which is mounted a valve 26 controlling the flow from the receptacle 2. From the valve 26 is continued a delivery gas pipe 27 in which there is mounted a valve 28, Fig. 3, 35 designed to hold a predetermined back pressure in the gas line and receptacle 2; the valve, in this case, being provided with a weight lever arm 29 connected to the stem 30 of the valve.

40 Oil is discharged from the receptacle through an adjustable outlet consisting, in this case, of an elbow 31 turnable about an axis in the connection 32 which is extended to the outside of the receptacle 2 and has a downturned branch 33 leading into an oil regulating valve 34 from which the oil passes into a delivery pipe 35.

One of the features of the present invention resides in means for very carefully 50 adjusting the level of the outlet member 31 as by swinging it about its axis in the member 32; and to secure this refinement of adjustment the outlet member has attached to it a link or rod 36 extending up through a 55 guy 37 and thence through a bearing 38, Fig. 2, to which is attached a yoke or other suitable member 39 to which is rotatively secured a handwheel 40 that engages the upper threaded end 41 of the rod 36. Therefore, by turning the handwheel 40 in one or the other direction it will lift or lower the rod 36 and consequently set the opening of the outlet member 31 at a desired position so as to enable the separation or outflow of the oil at or above a desired predetermined

level with respect to the liquid content of the receptacle 2, as it is obvious that the oil will vary in clarity according to the specific gravity of its constituents and the upper portion of a mass of oil is therefore 70 clearer than the lower portion, and to secure the separation of this clearer or better quality the outlet member 31 is made adjustable.

A further feature of the present invention resides in the provision of a buoyant yet 75 substantial means for automatically controlling the opening and closing simultaneously of the gas outlet valve 26 and the oil outlet valve 34, and to that end these valves are shown as mounted on a common rock shaft 80 45 on which is provided a lever 46 to the outer end of which is connected a link 47 the upper end of which is attached at 48 to a lever arm 49 on which may be adjusted a counterbalancing weight 50.

The lever arm 49 is secured to the contiguous end of a short rock shaft 51 mounted in a box 52 attached to the side of the receptacle 2 this box having diverging walls forming a mouth opening to the interior of 90 the receptacle 2, and in this mouth there oscillates a lever 53 attached to the portion of the shaft 51 extending into the box 52. The swinging end of the lever 53 is pivotally connected at 54 to a bearing 55 that 95 is attached to the adjacent side of a pneumatic cylinder 56.

For the purpose of stabilizing and maintaining this pneumatic cylinder in a vertical position it has connected to it at 57 the side 100 arms of a yoke 58 which has rearwardly extending parallel arms 59 these being pivoted on a bearing 60 arranged within the receptacle 2; the length of the lever device 58 and the lever 53 being substantially equal 105 and therefore holding the float 56 in an upright position and causing it to move in a vertical position at all times as determined by variation of the level of the oil in the receptacle 2.

110 As above mentioned there is maintained in the receptacle a gas pressure as determined by the adjustment of the pressure regulating valve 28, and it is desirable to provide, therefore, a pneumatic float as 56 115 which will not only be of a highly buoyant characteristic but also will be able to withstand the exterior pressures applied without crushing, and therefore, the float 56 is made in the form of a hollow cylinder and has at 120 its upper end a check valve 61 that may be covered by a removable cap 62, and the pneumatic float 56 may be charged with compressed air or gas to any desired degree or equal to the maximum at which pressures 125 would be maintained in the receptacle 2.

The operation of the apparatus is substantially as follows:

The valve 28 having been set by its regulating means 29 to hold a given pressure in 130

the receptacle 2 then as oil and gas is supplied to the receptacle by the oil supply pipe 12 the latter will be directed down the small compartment through the inlet or feed sleeve 15 by which the oil is showered on to the adjacent portion of the receptacle wall whence it flows downwardly between the wall and the partition 19 any gases being liberated rising to the top of this compartment and passing over the upper end of the partition 19 and accumulating in the upper end of the receptacle 2.

The oil mass, or emulsion in some cases, passes beneath the lower end of the partition 19 and thus facilitates the deposit or separation of solids such as sand or other heavy substances, and the lighter portion of the oil with the gas and the emulsion rises into the larger compartment of the receptacle and passes upwardly to a level that is determined by the position of the pneumatic float 56. The gas will be compressed to a pressure substantially equal to that determined by the valve 28 and maintained there, and as the oil accumulates it will lift the float 56 and through means of the lever arm 53 rock the rock shaft 51 and through means of its connection to the valve shaft 45 rock the latter so as to open or increase the opening of the oil valve 34 and permit the discharge of oil through the outlet member 31 past the valve 34 and to the discharge 35. Thereupon the level of the oil will fall until in such action the float 56 in descending will again close or partially close the oil valve 34 and open or increase the opening of the gas valve 26. This alternate action of the automatic valve mechanism will continue so long as oil is supplied by the main oil pipe 13 to the apparatus.

From the above it will be seen that I have provided a method for separating or facilitating the separation of the gas and oil and separately discharging the same from emulsions; and furthermore have provided a method in which, by maintaining a predetermined pressure in the oil receptacle, the latter is subjected to pressures having the effect of expressing the gaseous content from emulsions, the gaseous constituent in the emulsion being driven from the denser liquids by the increase in the pressure on the oil within the receptacle 2. This, therefore, prevents the loss of the valuable gaseous constituent such as occurs in apparatus in which the oil passes immediately from a well or other source to an apparatus in which it is subject only to atmospheric pressure.

In the event of treating oils that are not emulsified the valve 34 may be omitted or may be fixed open and a static head or pressure may be secured by maintaining a column of oil in the discharge pipe 35 by providing the latter with a safety extension 35^a.

This extension is shown as in the form of a

U-shaped pipe stem that is turnable from a horizontal to an upright position about the axis of the pipe 35 and may be temporarily and substantially secured in its angular adjustment by a suitable jack comprising for instance a post 35^b having a sleeve 35^c the upper end of which engages the cross or top section of the siphon tube as at 35^d.

For the purpose of breaking the siphon effect in one branch as 35^e of the tube an inwardly opening check valve 35^f is mounted, preferably, in the bend of the siphonic device so that the oil will not be drawn from the branch to which the pipe 35 is connected but will be maintained therein to prevent drawing out of the gas from the receptacle 2.

Preferably water is maintained in the bottom of the receptacle to a level somewhat above the lower end of the sand sheet or partition so that the incoming supply of oil when passing below the lower end of the partition is brought into contact with the water and the attrition between the emulsion causes a rapid separation of the gaseous content as the oil and mixture engages the water.

It has been found from practical experience in the operation of this apparatus that there is an increase in the production of oil from some wells because of the back pressure in the well line which prevents the rapid increment in the quantity of sand ordinarily found in wells, and which increment results in the clogging or jamming of the well and loss of production until the well is blown.

The sand sheet 19 is, preferably, provided with a window opening that may be covered by a cover plate 19^a through which the member 15 may be applied and removed when necessary.

Various changes may be made without departing from the spirit of the invention as claimed.

What is claimed is:

1. In an apparatus for separating gas and oil from oil wells comprising a receptacle, a vertical partition arranged in the receptacle and terminating short of the top and bottom of the receptacle, and means arranged between the said partition and a contiguous wall of the receptacle for introducing the oil from the well whereby the oil is caused to flow downwardly and around the lower end of the partition and rise on the opposite side and the gas that freely escapes from the oil rising to the top of the receptacle and collecting above the upper end of the partition; said means including an inlet oil tube arranged in the upper part of the receptacle, said tube having a surrounding discharge sleeve with a deflecting bottom plate for discharging the oil toward the receptacle wall.

2. In an apparatus for separating gas and oil from oil wells comprising a receptacle,

- a vertical partition arranged in the receptacle and terminating short of the top and bottom of the receptacle, and means arranged between the said partition and a contiguous wall of the receptacle for introducing the oil from the well whereby the oil is caused to flow downwardly and around the lower end of the partition and rise on the opposite side and the gas that freely escapes 5 from the oil rising to the top of the receptacle and collecting above the upper end of the partition; said means including an inlet oil tube arranged in the upper part of the receptacle, said tube having a surrounding discharge sleeve with a deflecting bottom plate for discharging the oil toward the receptacle wall; said sleeve having upper and lower outlets for gas and oil respectively.
3. In an apparatus for separating oil and gas, a receptacle having separate discharge means for the oil and gas, each having an exterior valve actuated by a common crank, said valves being set for one to open as the other closes and float means within the receptacle actuated by the height of the liquid, operatively connected to said crank to actuate said valves.
4. In an apparatus for separating oil and gas, the combination of a receptacle having oil inlet means, separate oil and gas outlet means comprising pipes extending from the interior of said receptacle, stop cocks arranged in said pipes, one to open as the other closes and actuated by a common crank, float means within the receptacle operatively connected to said common crank adapted to actuate the valves with reference to the height of the liquid within the receptacle.
5. In an apparatus for separating gas and oil the combination of a receptacle, a float within the receptacle for actuating gas and oil outlet valves, said float comprising a sealed chamber, two supporting arms of equal lengths pivoted to said float at their proximal ends and pivoted to the wall of the receptacle at their distal ends to hold the chamber in substantially vertical alinement during movement thereof, the pivotal centers of said arms being off-set in vertical alinement at their distal ends, one of said arms having an extension thereon extending through the wall of the receptacle and being operatively connected to an actuating arm of said valves.
- In testimony whereof I have signed my name to this specification.

DAVID G. LORRAINE.
